UNITED STATES PATENT OFFICE.

FREDERICK A. WRIGHT AND WALLIE J. BRONG, OF DICKSON CITY, PENNSYLVANIA.

ELECTRICAL GRADE-CROSSING SIGNAL.

1,313,445.

Specification of Letters Patent. Patented Aug. 19, 1919.

Application filed June 1, 1917. Serial No. 172,279.

To all whom it may concern:

Be it known that we, FREDERICK A. WRIGHT and WALLIE J. BRONG, citizens of the United States, residing at Dickson City, 5 in the county of Lackawanna, State of Pennsylvania, have invented a new and useful Electrical Grade-Crossing Signal, of which the following is a specification.

The present invention appertains to signals 10 and semaphores, and aims to provide a novel and improved signal adapted especially for use at grade crossings, although useful for various other purposes.

It is the object of the invention to provide 15 a signal of novel and improved construction for signaling to traffic, whereby to avoid accidents, and having improved operating means associated with the signal member.

20 With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

25 The invention is illustrated in the accompanying drawings, wherein:—

Figure 1 is an elevation of the improved signal.

Fig. 2 is a cross section thereof on the 30 line 2—2 of Fig. 1.

Fig. 3 is a longitudinal section on the line 3—3 of Fig. 2.

Fig. 4 is a sectional detail of the operating mechanism on the line 4—4 of Fig. 3.

40 Fig. 5 is an elevation of the electromagnet of the operating mechanism.

Fig. 6 is a sectional detail on the line 6—6 of Fig. 3, illustrating the circuit closing means of the bell or alarm.

45 Fig. 7 is a diagrammatical view illustrating the circuit of the bell or alarm.

The signal embodies a suitable casing 1, which can be supported on a post, a bracket, or the like, said casing being provided with 50 a gable roof 2, the edge portions of which are bent to provide eaves 3 for catching the rain water and discharging the same from the ends thereof. As shown, the roof is of sheet metal, and the walls of the casing are 55 of wood, although any suitable materials can be used. The side walls of the casing

are provided with windows 4 to expose the signal member 5 which is operable within the casing. This signal member is in the form of hollow light-containing drum provided with paneled sides, and is rotatable about a longitudinal axis. The signal member comprises the end disks 6 connected by four strips 7 adjacent to the margins of said disks, and opposite panels 8 and 9 have their 60 edges secured to said strips, which are preferably provided with rabbets 10 for receiving the edges of the panels. The panels 8 are each provided with the word "Stop" and may be colored red, while the panels 9 70 are each provided with the word "Go", although the panels can be provided with any suitable legends or signs.

In order to mount the signal member for rotation, one end disk 6 thereof is provided 75 with a bearing 11 rotatable upon a tubular member 12 extending through one end of the casing and carried by a bearing 13 secured to said end of the casing. The other end disk 6 of the signal member has a bearing 14 rotatable upon a spindle 15 secured to a bearing 16 fastened to the other end of the casing. The signal member can thus be rotated or turned to bring either the panels 8 or the panels 9 behind the windows, to 85 indicate when the traffic should stop or proceed.

A source of light is mounted within the signal member to illuminate the panels thereof, and for this purpose hangers 17 are 90 pivotally engaged at their upper ends with the tubular member 12 and bearing 14, and have attached to their lower ends a bar or beam 18 carrying one or more lamp sockets 19 to which electric lamps 20 are applied in 95 an upstanding position. The conductors 21 of the lamps are extended through the tubular member or spindle 12. The hangers 17 with the bar 18 provide a U-shaped member suspended loosely within the signal member to remain in pendent position while the signal member rotates. The tubular spindle 12 serves to lead the conductors through the end wall of the casing from the exterior and also to the end wall of the signal member. 100

One end of the casing has an opening 22 above the tubular spindle 12, across which a lens or bull's eye 23 is mounted, the passage of the light rays through the openings 22 being prevented when the "go" panels 110 9 are moved behind the windows 4. The corresponding end disk 6 of the signal mem-

ber, however, is provided with an opening 24 which registers with the opening 22 when the signal member is turned to bring the "stop" panels 8 behind the windows, whereby the light rays can pass through the openings 22 and 24 and lens 23 to provide a signal, when the signal member is in danger position. This lens 23 and pair of openings can be provided at either end of the casing. 10 The disks 6 are opaque to prevent the passage of light through the lens 23, excepting when the opening 24 registers with the opening 22.

As a means for operating the signal member, the bearing 14 is provided with a pinion 25 at the outer side of the respective end of the signal member, and a lever 26 is fulcrumed or pivoted, as at 27, to the corresponding end of the casing at the inner side thereof, and is provided at one end with an arcuate rack 28 meshing with the pinion 25, whereby the oscillatory movement of the lever 26 will rotate the pinion 25 and signal member to which it is fastened. The lever 25 20 is disposed between the end of the signal member and casing and is operated by electromagnet 29 disposed on the bottom of the casing underneath the signal member. An armature 30 under the influence of the magnet is hung pivotally, as at 31, and is provided with an arm or lever 32 overhanging the magnet and connected by a link 33 with that arm of the lever 26 opposite to the rack 28. A spring 34 connected with 30 the lever and casing, returns the operating mechanism to normal position when the electromagnet is deenergized, the rack 28 being raised, whereby to turn the signal member to one position. When the magnet is energized, it will attract the armature 30, and raise the arm 32, whereby to raise the link 33 and corresponding arm of the lever 26. The rack 28 will, therefore, be moved downwardly, to turn the pinion 25 and signal 40 member to bring the other pair of panels behind the windows 4. The signal member is thus controlled by the electromagnet 29 which can be energized and deenergized by the closing and opening of an electrical circuit 35 having a switch 36 or other suitable means controlling it.

A bell 37 or other electrical audible signal is preferably used, to call attention to the signal when in danger position. This 50 bell or alarm is mounted within the casing, and is disposed in a circuit 38. In order to close the circuit 38 when the signal member is turned to danger position, a block 39 of insulating material is attached to one end 60 of the casing and carries a pair of diverging leaf spring contacts 40 to which two conductors of the circuit 38 are connected. A contact 41, preferably in the form of a

roller, is carried by a pin 42, which is in turn carried by the corresponding end disk 6 of the signal member, and this roller 41 moves snugly between the contacts 40 when the signal member is turned to danger position, thereby closing the circuit of bell 37. A buffer 43 is carried by the corresponding end wall of the casing in the path of movement of the roller 41, whereby to cushion and stop the movement of the signal member when the armature 30 is released from the magnet 29. 75

One end of the casing is provided with binding posts 44 on the outside thereof for the connection of the conductors.

In operation, when the magnet 29 is energized due to the closing of the circuit, this will turn the signal member to danger position, in which event the contact 42 engages the contacts 41 and closes the circuit of the bell 37 which will operate to call attention to the signal. At the same time, the opening 24 of the signal member registers with the opening 22 for the passage of light through the lens 23. As soon as the magnet 29 is deenergized, the parts will return to normal safety position. In the night 90 time, the circuit of the lamps 20 can be closed, whereby the panels will be illuminated. This is unnecessary, however, during the day time.

Having thus described the invention, what is claimed as new is:—

1. A signal embodying a casing having a window at one side and an opening at one end, a drum-shaped signal member mounted for rotation within the casing behind said window and having an opening at one end normally out of register with the opening in the casing and adapted to register with the opening in the casing when the signal member is turned to one position, whereby rays of light may be projected through the opening in the casing, and a source of light within the signal member. 100

2. A signal embodying a casing having a window at one side and an opening at one end, a source of light within the casing, a signal member within the casing and movable behind the window, and normally closing the opening to the projection of rays of light therethrough, and means for moving the signal member to display a signal through the window and uncover the opening to emit rays of lights. 110

In testimony that we claim the foregoing as our own we have hereto affixed our signatures in the presence of two witnesses.
